UNITED STATES PATENT OFFICE.

JOSEPH KELLER, OF BUFFALO, NEW YORK.

BUFFING-MACHINE.

1,392,172.

Specification of Letters Patent. Patented Sept. 27, 1921.

Application filed May 24, 1919. Serial No. 299,585.

To all whom it may concern:

Be it known that I, JOSEPH KELLER, a citizen of the United States of America, residing in the city of Buffalo, county of Erie, and State of New York, have invented 5 certain new and useful Improvements in Buffing-Machines, of which the following is a full, clear, and exact description.

My invention relates generally to buffing 10 machines and more particularly to machines for buffing objects having curved surfaces which are rotated while being buffed.

The principal object of my invention has been to provide a machine of this type in 15 which the work shall be automatically moved back and forth across the buffing wheel at a constant rate of speed, while it is being rotated.

Another object has been to provide a machine 20 provided with a plurality of work-piece holders or chucks, whereby finished work-pieces may be removed and unfinished pieces chucked in the machine while it is operating upon other work-pieces.

Another object has been to provide a machine 25 in which the time required to change work-pieces may be reduced to a minimum whereby the output of the machine is greatly increased.

Furthermore, my invention is so designed 30 as to be easily operated, and is of such sturdy construction that it will not easily get out of order.

The above objects and advantages, as well 35 as others which will be apparent to those skilled in the art, have been accomplished by the device shown in the accompanying drawings, of which:

Figure 1 is a side elevation of my device, 40 partly in section.

Fig. 2 is an end elevation of the same.

Fig. 3 is a fragmentary sectional plan view taken on line 3—3 of Fig. 1, showing the actuating-screws.

Fig. 4 is an enlarged side elevation of the 45 actuating-screw bracket.

Fig. 5 is an enlarged sectional end elevation taken on line 5—5 of Fig. 3, showing the parts illustrated in Fig. 4.

Fig. 6 is an enlarged, fragmentary, sectional view of the work-support and is taken 50 on line 6—6 of Fig. 2.

Fig. 7 is an enlarged view of the work-support stem and its indexing device.

Fig. 8 is a fragmentary, sectional, plan

view taken on line 8—8 of Fig. 6 and showing a work-support, quick release.

Fig. 9 is an enlarged view of some of the details of the work-support, quick release.

Fig. 10 is an enlarged, fragmentary end 60 elevation of the lower portion of the work-support, and is taken on line 10—10 of Fig. 1.

Fig. 11 is an enlarged view of some of the details of one of the chuck-brackets. 65

Fig. 12 is an end view of the same.

Figs. 13, 14 and 15 are enlarged, detailed views of the chuck operating mechanism.

My device comprises in general, a buffing standard having two wheels; a work-support 70 arranged in front of each wheel; and means for actuating the work-support and the chucking devices.

The buffing standard comprises a housing 20 which supports the elements of the device. A spindle 21 is rotatably mounted in suitable bearings formed in the upper part of the standard and is provided with a tight pulley 22 and a loose pulley 23, whereby power is connected to the machine. A buffing wheel 24 is carried by each end of the spindle 21. The tight pulley 22 is provided at one end with a peripherally reduced portion, forming a pulley 25, which is connected to a pulley 26, mounted upon a jack-shaft 27 by means of a belt 28. The jack-shaft is suitably journaled within the housing 20. 80

29 is the main shaft of my device which is rotatably mounted within the housing 20 90 and is provided with suitable collars to prevent end motion. The jack shaft is connected with the main shaft by a train of gearing, comprising gears 30, 31, 32 and 33. 34 is a gear housing which is preferably secured to the end of the housing 20, whereby the gears will be protected and may be submerged in oil or grease. 95

Each end of the main shaft 29 extends outwardly for some distance beyond the 100 housing 20, and mounted to slide upon each end of this shaft is a work-support 35. Each end of the main shaft 29 is provided with a key-way 36. A bevel gear 37 having a sleeve 38 is mounted upon each end of the shaft 105 and a key 39, carried by the sleeve 38, engages with the key-way 36, whereby the sleeve may slide axially upon the shaft but will rotate therewith. (Fig. 6.) A work-support bracket 40 is mounted upon the 110

sleeve 38 of the bevel gear and a collar 41, carried by the sleeve, prevents the bracket from moving thereon. Rotatably carried by the bracket 40 is a shaft 42, which is arranged at right-angles to the main shaft 29. A bevel gear 43, secured to the lower end of the shaft 42 engages with the bevel gear 37 whereby the shaft 42 is driven. A work-support stem 44 surrounds the shaft 42 and its lower end 45 is rotatably mounted within the bracket 40, and held against rotation by suitable index means to be hereinafter described. At the upper end of the stem 44 is mounted a mandrel-head 46. This head 15 is adjustably carried by the stem 44 and provided with locking means 47, (Fig. 1,) whereby it may be adjusted to any angle, relative to the main shaft, and securely locked in its adjusted position. The mandrel-head 46 is provided with two oppositely arranged bearings 48 having mandrel-shafts 49 and 50 rotatably disposed therein. The shaft 50 is preferably provided with a peripherally reduced end 51, which is disposed within a centrally arranged bore 52 of the shaft 49, whereby additional support for the ends of these shafts is obtained. A bevel gear 53 is mounted upon the inner end of each of these shafts. A bevel gear 54 25 is secured to the upper end of the shaft 42 and is in engagement with the bevel gears 53, whereby the mandrel-shafts 49 and 50 will be rotated in opposite directions. A mandrel 55 is secured to the outer end of 30 each of the shafts 49 and 50.

Each of the brackets 40 is provided on its side, facing the housing, with an arc-shaped extension 56, having an arcuate slot 57, of T-shaped cross-section. The head 58 of an 40 actuating-screw 59, to be hereinafter described, is engageable with the T-shaped slot 57 of each of the work-support brackets 40. Each of the work-supports 35 is maintained in its normal working position by 45 means of a weight 60. A rope or cable 61, having one end attached to the weight and the other end attached to the work-support stem 44, passes over a pulley 62, carried by the housing 20, (Fig. 2.)

64 is a detent arm, having a boss 65 which is rotatably mounted upon the end of the main shaft 29 and adjacent to the work-support bracket 40. The detent arm 64 is also provided with a boss 66 within which the actuating-screw 59 is rotatably disposed. The detent arm of each of the supporting brackets 40, is thus rigidly held against rotation by the shaft 29 and screw 59. The 55 detent arm 64 extends rearwardly and at its extreme end it is provided with an outwardly extending boss 67. An adjusting nut 68 having a stem 69 is mounted within the boss 67 in such a manner that it may freely oscillate. A work-support adjusting screw 70 60 extends rearwardly and at its rear end engageable with the nut 68.

and is supported near its forward end by means of a bracket 71, secured to the work-support bracket 40 by means of a bolt 72, permitting a slight oscillatory motion. A stop collar 73, (Figs. 8 to 10,) is secured to the screw 70 and bears against the rear face of the bracket 71. The forward end of the screw extends to a point within easy reach of the operator, and is there provided with a suitable hand-wheel 74.

A quick release 75 for the work-support is provided, as shown in Figs. 8 to 10, so that the mandrels bearing the work-pieces may be quickly thrown away from the buffing wheels and quickly moved back to the same 80 position for operation upon a new work-piece. These means comprise a cam arm 76, pivotally attached by the bolt 77 to a bracket 78 carried by the work-support bracket 40. The cam arm 76 is provided at its inner 85 end with a circularly-shaped cam 79. This cam engages with a stud 80 carried by a yoke 81. 82 is a release collar, mounted upon the screw 70 and provided with an annular groove, with which the yoke 81 is in engagement, whereby the screw 70 may be moved in or out of the nut 68, and the distance between the stud 80 and the bolt 77 will be maintained substantially uniform. When the cam arm 76 is pushed to the right of the 90 position shown in Fig. 8, the cam 79 will serve to push the lever, and hence the work-support 35 away from the release-collar 82 and the stop-collar 73, whereby the work-piece will be moved out of contact and some 95 distance away from the buffing wheel. When a new work-piece is ready to be buffed, the cam arm 76 is moved back to the position shown in Fig. 8, which operation causes the work-support to be returned to the position 100 shown, and the movement will be stopped by the engagement of the bracket 71 with the stop-collar 73. It will be understood that the screw 70 is never moved except when it is desired to change the relative location of 105 the mandrel 55 and the buffing wheel 24. When the work support is moved as just described, the end of the actuating-screw 59 with its head 58 will be moved through the 110 slot 57 of the work-support bracket 40.

As hereinbefore stated, each mandrel-head of my device is provided with two mandrels. One of these mandrels is idle while the opposite mandrel is holding a work-piece in contact with the buffing wheel. The finished work-piece held by the idle mandrel may be removed and another work-piece placed thereon during the time the other mandrel is in operation. So as to bring these mandrels alternately into operating position with the buffing wheel, the index device, hereinbefore referred to, is used. By reference to Figs. 6 and 7 it will be seen that the lower end 45 of the work-support stem 44 is provided with two dia- 115

metrically opposite index-holes 85. These holes are preferably tapered and are engaged by an index pin 86. This pin is slidably arranged within a hollow boss 87, carried by the work-support bracket 40 and is pressed inwardly and in engagement with either one of the holes 85 by means of a spring 88. The pin is provided with a peripherally reduced end 89, which extends 10 through a plug 90. Two oppositely arranged spring fingers 91 are attached at their inner ends to the end 89 of the index pin. The outer ends of these fingers are tapered and provided with catches 92. The 15 index pin with its fingers 91 is so located that the cam arm 76, when in its normal position, will lie between the fingers. The cam arm is provided with a boss 93 on each of its sides where it passes between the fingers, 20 and these bosses engage with the catches 92 of the fingers when the cam arm is operated as hereinbefore described. When the cam arm is moved, as above described, the bosses 93 are engaged with the fingers 92 25 until the index pin has been drawn out to the limit of its travel, whereupon a further movement of the arm will cause the fingers to spread, whereby the arm will be disconnected and allowed to move through its 30 maximum stroke. The bosses 93 and the ends of the springs 91 are tapered, so that when the cam arm 76 is returned it will force the spring fingers open and allow the arm to pass between them.

35 In the bottom of the work-support stem 44 is provided a tapered bore 94. Engageable with this tapered bore is a tapered plug 95, which is slidable upon the shaft 42, but prevented from relative rotation therewith 40 by means of a pin 96. The pin 96 is carried by the shaft 42 and engages with a slot 97 formed in the plug 95. The work-support bracket 40 is provided immediately below the plug 95, with a counterbore 98, in which 45 is disposed a spring 99. This spring serves to keep the plug 95 pressed in frictional contact with the tapered bore 94 of the stem 44. The stem 44 is, of course, normally held against rotation by means of the index pin 50 86, but the shaft 42 and the tapered plug 95 are continually rotating. It will be clearly seen that when the index pin is withdrawn, the frictional engagement of the rotating plug 95 will cause the stem 44 to rotate. By this time it has moved through 55 180° the index pin 86 will have been released from its engagement with the cam arm 76 and it will engage with the opposite index-hole 85 and retain the stem in its new position.

60 The actuating-screws 59 and 59^a are each mounted within the housing 20 so as to rotate and reciprocate axially. The actuating-screw 59 passes through the housing 20 and 65 gear-housing 34 and a spur gear 100, ar-

ranged between the two housings, is mounted upon this screw. The gear carries a key (not shown) which engages with a key-way 101 in the screw. The gear 100 meshes with a gear 102, mounted on the main-shaft 29, 70 whereby this actuating-screw is rotated. The actuating-screw 59^a passes through the sleeve 103 of a gear 104, and a key 105, carried by the sleeve 103 engages with the key-way 106 formed in this screw. The 75 sleeve 103 is rotatably mounted within the housing 20 and end motion thereof is prevented by a collar 107. The gear 104 meshes with a gear 108 carried by the main-shaft 29, whereby the actuating screw 59^a is rotated. 80 As hereinbefore stated, the outer end of each of these actuating screws is provided with a head 58, which engages with the slot 57 of the work-support bracket 40. Substantially 85 one-half of each screw near this end is provided with the key-way just described. The other end of each of the screws, for substantially one-half the length thereof, is provided with a right and left hand screw-thread 109 and 110, respectively. 90

The actuating-screws 59 and 59^a lie preferably in the same horizontal plane and an actuating-screw bracket 111, is arranged between them and preferably at the longitudinal center of the housing, (Figs. 3-5.) 95 The actuating-screw bracket 111 is adjustably mounted upon a rod 112, carried by the housing 20, and it is provided with two longitudinally arranged bores 113. In each of the bores 113 are arranged two actuating-nuts 114 and 115. These nuts are rotatably mounted within the bores and each is provided with a thread, engaging, respectively, with the right and left-hand screw-thread on the actuating-screws. Each of 100 these nuts is provided with a collar 116, arranged at its outer end and formed with a V-shaped groove 117. Arranged at each side of the housing is a friction yoke 118. Each of these friction yokes have two bifurcated and downwardly extending arms 119. These arms are provided with a circular face and are V-shaped to correspond to the V-shaped groove 117 of the nuts 114 and 115. The width of the actuating-screw 115 bracket 111 is such that when the arms 119 are in engagement with the nuts, there will be a slight end play between the collars 116 of the nuts and the bracket, so that the friction yoke will oscillate about its pivotal 120 point. The parts of this device are so arranged and proportioned that when the collar 116 of, for instance, the nut 115, (Fig. 4,) is in engagement with the face of the bracket 111, the bifurcated arm 119 engaging 125 with this nut, will frictionally hold the nut against rotation within the bracket 111. When the nut is thus held the actuating-screw will be moved relative to the stationary bracket 111 and will thus reciprocate 130

the work-support bracket attached thereto. It will be seen by referring to Fig. 4 that the collar 116 of the nut 114 is moved away slightly from contact with the end of the bracket and that the arm 119 engaging with this collar is also out of frictional contact with the groove thereof, so that this nut will be free to rotate within the bracket and with the actuating-screw, without imparting axial movement to the screw. Adjustable reverse collars 120 are provided on the actuating-screws, and when each screw has been moved through its predetermined amount of travel, one of these collars will come into contact with the rotating nut, for instance, the nut 114 of Fig. 4 and move both nuts endwise, thereby relieving the nut 115 and causing the yoke 118 to frictionally grasp the nut 114, whereby this nut will become active and the opposite one inactive. The actuating-screw will thus be reversed in its axial movement, and it will be again reversed when it has moved its predetermined amount of travel in this direction. The actuating-screws are automatically reciprocated back and forth until operation upon the work-piece is finished.

Carried by each of the mandrel-heads 46 is a chuck-bracket 123. Each of these brackets comprises a standard 124 secured at its lower end to the mandrel-head 46. A cam stud 125 is supported by the standard 124 and is arranged parallel with the mandrel shafts. A quick acting chuck is mounted upon each end of the stud 125, and arranged to engage with the work-piece mounted upon the mandrel. By reference to Fig. 1 and Figs. 11 to 15 it will be seen, that each quick acting chuck comprises a chuck arm 126 carried by a head 127. The head is rotatably mounted upon the end of the stud 125 and is provided with a pin 128, which engages with a cam-shaped slot 129 formed in the end of the stud. This cam is formed with parallel grooves 130 and 131 arranged at opposite sides of the stud and connected by a spiral-shaped groove 132. The cam stud 125 is locked in position and as the head 127 is pushed endwise on the stud the pin 128 will travel along the groove 130 then along the spiral groove 132, which will rotate the chuck arm 126 through substantially 180°, (Fig. 12) and then along a portion of the groove 131. The head 127 is provided with an annular groove 133 with which a yoke 134 is engageable. A link 135 is pivotally mounted at one end upon a bracket 136. This bracket is attached to and carried by the cam stud 125. The outer end of the link 135 is provided with a slot 137 which engages with a pin 138 carried by the yoke 134. An operating lever 139 is pivotally attached to the bracket 136, and a link 140 connects this lever with the link 135. By this arrangement, when the lever 139 is op-

erated to the dotted position shown in Fig. 13, the chuck arm will be moved away from the mandrel and rotated to an upward position where it will be out of the way and permit the workman to easily remove the finished work-piece from the mandrel and to place thereon a new work-piece. The chuck arm 126 is provided with a longitudinal slot 141, in which are arranged preferably two bearing collars 142. These bearing collars are movable up and down within the slot and are adjusted in position by means of a nut 143. Passing through each of the bearing collars is a chuck finger 144. Each of these fingers is provided at its outer end with a disk 145, and a spring 146, is arranged beneath the disk and between it and the bearing collar. A retaining nut 147 is secured to the outer end of each finger, whereby it is prevented from being forced out of the bearing collar. These chuck fingers are adjusted so that their axes will lie slightly beyond the outer periphery of the mandrel 55 or the work-piece secured thereto, as shown in Fig. 11. This will permit the fingers to be rotated by the moving work-piece and thus provide rolling contact with the work-piece. The parts are so adjusted that the springs 146 are placed under tension when the chuck is in its normal position.

When my machine is in operation the work-supporting brackets 40 will be automatically reciprocated at a constant rate of speed, thus carrying one of the chucks of each head back and forth across the buffing wheels. While the work-piece carried by this chuck is being acted upon, an unbuffed work-piece is placed upon the chuck at the opposite end of the mandrel-head and the quick acting chuck operated, as hereinbefore described, to hold the same in position upon the mandrel. When the work-piece being operated upon is finished, the cam lever 76 of the work-support, quick release 75 is operated, which will swing the work-support carrying the mandrel-head, away from the buffing wheel and almost simultaneously withdraw the index pin 86 from its engaging hole. As the workman continues to move the cam lever, the work-support will be swung to its maximum inoperative position. During this time the tapered plug 95 will have rotated the mandrel-head, and the same will have been locked in its new position by the index pin 86. The cam lever 76 is now returned to the position shown in Fig. 8, whereupon the chuck, bearing the new work-piece, will be brought into operative position. These operations are accomplished very quickly and with great ease, whereby a large amount of work may be buffed. While I have described the operation of but one mandrel-head, it is obvious that the work-pieces of both work-sup-

75

100

110

115

120

125

130

ports may be changed alternately while the two work-pieces are being buffed at one time. The mandrel-heads 46 may be moved around axially so as to adapt the machine to the buffing of different shaped work-pieces. As for instance when buffing the tapered periphery or the face of work pieces.

While I have shown but one cam stud for the two chucks, it is obvious that I may provide a separate stud for each chuck so that it may be moved axially to bring the cam thereof in proper position for different kinds of work-pieces. These and other modifications of the details herein shown and described may be made without departing from the spirit of my invention or the scope of the appended claims; and I do not therefore wish to be limited to the exact embodiment herein shown and described, the form hereinbefore described being merely a preferred embodiment thereof.

Having thus described my invention, what I claim is:

1. A buffing machine, comprising a spindle, a buffing wheel carried by the spindle, a plurality of work-piece chucks, releasing means for the chucks, means, controlled by the releasing means, for alternately placing the chucks, one at a time, into working position, means for rotating the chucks, and means for reciprocating the chucks.

2. A buffing machine, comprising a spindle, a buffing wheel carried by the spindle, a work-support, a work-piece chuck carried by the support, means for holding the support in its operative position, cam means for quickly releasing the work-support and moving it to its inoperative position, and means for reciprocating the work-piece.

3. A buffing machine, comprising a spindle, a buffing wheel carried by the spindle, a work-support, a plurality of work-piece chucks, carried by the support, cam means for quickly releasing the support and moving it away from its operative position, and means for simultaneously moving one of the chucks, carrying an unfinished work-piece, into operative position.

4. A buffing machine, comprising a spindle, a buffing wheel carried by the spindle, a mandrel for the work-piece, and a cam actuated chuck associated with the mandrel.

5. A buffing machine, comprising a spindle, a buffing wheel carried by the spindle, a mandrel for the work-piece, and a quick-acting chuck associated with the mandrel, comprising a chuck arm having fingers engageable with the work-piece, and cam actuated means for moving the arm clear of the mandrel.

6. A buffing machine, comprising a spindle, a buffing wheel carried by the spindle, a mandrel for the work-piece, and a quick-acting chuck associated with the mandrel, comprising a cam stud, a chuck arm mount-

ed upon the stud and engageable with the cam thereof, and means for moving the cam arm axially upon the stud, whereby it will be moved clear of the mandrel.

7. A buffing machine, comprising a spindle, a buffing wheel carried by the spindle, a mandrel for the work-piece, and a quick-acting chuck associated with the mandrel, comprising a chuck arm, a plurality of chuck fingers adjustably carried by the chuck arm, each chuck finger being rotatably mounted in the chuck arm, and a spring for each finger, whereby the fingers will bear flexibly against the work-piece.

8. A buffing machine, comprising a housing, a spindle rotatably mounted in the housing, a buffing wheel carried by the spindle, a work-support, comprising a bracket slidably carried by the housing, a stem carried by the bracket, a work-piece chuck mounted on the upper end of the stem, means for holding the chuck in its operative position, means for adjusting the angle of the chuck, and screw means for reciprocating the work-support at a constant rate of speed.

9. A buffing machine, comprising a housing, a spindle rotatably mounted in the housing, a buffing wheel carried by the spindle, a work-support, comprising a bracket carried by the housing, a stem carried by the bracket, a work-piece chuck mounted on the upper end of the stem, means for holding the chuck in its operative position, and quick release means for moving the chuck to its inoperative position.

10. A buffing machine, comprising a housing, a spindle rotatably mounted in the housing, a buffing wheel carried by the spindle, an oscillatory work-support, comprising a bracket carried by the housing, a stem carried by the bracket, a plurality of work-piece chucks mounted on the upper end of the stem, and index means for successively holding the stem and chucks in operative position.

11. A buffing machine, comprising a housing, a spindle rotatably mounted in the housing, a buffing wheel carried by the spindle, a work-support, comprising a bracket carried by the housing, a stem carried by the bracket, a plurality of work-piece chucks mounted on the upper end of the stem, means for rotating the stem, index means for successively holding the stem and chucks in operative position.

12. The combination with a buffing machine, of a work-support, comprising a bracket, a rotatable stem carried by the bracket, a plurality of work-piece mandrels at the upper end of the stem, means for rotating the mandrels, index means for the stem, and means for periodically rotating the stem whereby the mandrels are successively brought into operative position.

13. The combination with a buffing ma-

- chine, of a work-support comprising a bracket, a rotatable stem carried by the bracket, a plurality of work-piece mandrels at the upper end of the stem, a vertical shaft 5 passing through the stem for rotating the mandrels, friction means carried by the shaft and engaging with the stem for rotating the same, and index means for holding the stem in predetermined positions.
- 10 14. The combination with a buffing machine, of a work-support, comprising a bracket, a rotatable stem carried by the bracket, a plurality of work-piece mandrels at the upper end of the stem, a vertical shaft 15 passing through the stem for rotating the mandrels, a tapered plug carried by the shaft and engageable with the stem for rotating the same, and index means for holding the stem in predetermined positions.
- 20 15. A buffing machine, comprising a spindle, a buffing wheel carried by the spindle, a work-support, a work-piece chuck carried by the support, means for holding the support in its operative position, and an 25 adjusting screw for the work-support, means for quickly releasing the work-support and moving it to its inoperative position, comprising a release collar carried by the screw, and a cam arm carried by the support and 30 provided with a cam engaging with the release collar.
16. A buffing machine, comprising a housing, a spindle rotatably mounted in the housing, a buffing wheel carried by the 35 spindle, a work-support slidably carried by the housing and actuating means for reciprocating the support, comprising an actuating screw carried by the housing and provided with right-hand and left-hand screw- 40 threads, a bracket carried by the housing, a right-hand nut and a left-hand nut rotatably carried by the bracket and engageable with the screw, a yoke carried by the bracket and engageable with the nuts, and means carried by the bracket, whereby the yoke frictionally holds either one of the nuts against 45 rotation.
17. A buffing machine, comprising a housing, a spindle rotatably mounted in the 50 housing, a buffing wheel carried by the spindle, a work-support slidably carried by

the housing and formed with a T-shaped, arcuate slot, an actuating screw carried by the housing and provided with a head engaging the slot, and means for rotating the 55 screw.

18. A buffing machine, comprising a housing, a spindle rotatably mounted in the housing, a buffing wheel carried by the spindle, a work-support slidably carried by 60 the housing and formed with a T-shaped, arcuate slot, an actuating screw carried by the housing and provided with a head engaging the slot, means for rotating the screw, and means for axially reciprocating the 65 screw.

19. A buffing machine, comprising a housing, a spindle rotatably mounted in the housing, a buffing wheel carried by the spindle, a main shaft rotatably carried by 70 the housing, means for driving the main shaft, a work-support slidably carried by the main shaft, actuating means for reciprocating the support, a work-piece mandrel carried by the support, and means connect- 75 ing the mandrel with the main shaft.

20. A buffing machine, comprising a housing, a spindle rotatably mounted in the housing, a buffing wheel carried by the spindle, a main shaft rotatably carried by 80 the housing, a work-support slidably carried by the main shaft, an actuating-screw carried by the housing and connected with the work-support, means for driving the main shaft, means for driving the actuating 85 shaft, a work-support mandrel carried by the support, and means connecting the mandrel with the main shaft.

21. A buffing machine, comprising a housing, a spindle rotatably mounted in the 90 housing, a buffing wheel carried by the spindle, a jack-shaft rotatably carried by the housing, a work-piece chuck, means for connecting the jack-shaft with the chuck, for rotating the latter, and screw means for automatically reciprocating the chuck across 95 the face of the buffing wheel at a constant rate of speed.

In testimony whereof, I have hereunto signed my name.

JOSEPH KELLER.
